TIMING CONTROLLER

Carroll Stansbury, Wauwatosa, Wis., assignor to
 Cutler-Hammer, Inc., Milwaukee, Wis., a corporation of Delaware

Application May 16, 1939, Serial No. 273,957

10 Claims. (Cl. 175—375)

This invention relates to timing controllers, and while not limited thereto is particularly applicable to resistance welding control systems in which an impulse operated switch is used to control the period of power application in the welding circuit.

The invention has among its objects to provide an improved impulse operated switch for welding control systems of the aforesaid character which is exceedingly quick acting and reliable in operation and which is adapted to provide exceedingly short and accurately controlled periods of power application.

Another object is to provide an electromagnetically operated switch for use in systems of the aforesaid character having mechanical means associated therewith which is adjustable to provide selected periods of current flow in the resistance welding circuit upon energization of the switch by a unidirectional current impulse of given value.

Another object is to provide an electromagnetically operated switch of the double pole type having improved equalizing means associated therewith for insuring opening of the switch contacts simultaneously.

Various other objects and advantages of the invention will hereinafter appear.

The accompanying drawings illustrate an embodiment of the invention which will now be described, it being understood that various modifications may be made in the embodiment illustrated without departing from the spirit and scope of the appended claims.

In the drawings,

Figure 1 is a schematic view of a resistance welding control system having a switch embodying the invention associated therewith;

Fig. 2 is a front elevational view of a mechanical embodiment of the switch schematically shown in Fig. 1;

Fig. 3 is a side elevational view of the operating magnet shown in Fig. 1, a buffer device associated with the magnet being shown in section;

Fig. 4 is a sectional view on line 4—4 of Fig. 1, the switch being shown in open position;

Fig. 5 is a sectional view on line 5—5 of Fig. 1 illustrating the switch in closed position, and

Fig. 6 is a plan view of the movable contact element shown in Fig. 1.

Referring to Fig. 1, the same schematically illustrates a two pole switch embodying the invention, each pole including a stationary contact 1 and a cooperating movable contact 2. The movable contacts 2 are carried by a rotatable

operating shaft 3 having an operating magnet 4 associated therewith.

More specifically the movable contacts 2 are mounted upon opposite ends of a horizontally arranged equalizer lever 5 and are insulated therefrom, and said equalizer lever is pivotally mounted intermediate its ends upon a rocker arm 7. Equalizer lever 5 is adapted to swing in a substantially horizontal plane with respect to rocker arm 7 and said rocker arm extends downwardly and rearwardly from said equalizer lever and is pivotally mounted intermediate its ends upon a pin 8 carried by a lever 9 fixed to operating shaft 3. The lower end of rocker arm 7 is normally held in engagement with a stop projection 10 on lever 8 by a spring 11 which engages the under side of lever 5. Spring 11 is adjustable by a screw device 12 which is carried by a forwardly projecting lug 13 on lever 9.

Operating magnet 4 includes a fixed magnet frame 14, an operating winding 15 mounted upon said frame, and a movable armature member 16. Armature member 16 is adjustably secured to shaft 3 and is provided with a tail piece 17 which extends downwardly from said shaft and cooperates with a buffer device 18 of the character disclosed in the patent to Clarence T. Evans et al., No. 2,134,179, dated Oct. 25, 1938.

Briefly described the buffer device 18 is provided with a headed pin 19 having butt engagement with the tail piece 17 and connected to a piston 20 movable within a closed housing 21. Piston 20 is normally held against the front end of housing 21 by a spring 22 and the pin 19 associated with said piston acts as a stop to normally hold the movable switch parts against the action of gravity in a position to provide a relatively narrow air gap between the movable contacts 2 and their cooperating stationary contacts 1 and also between armature member 16 and magnet frame 14. Upon energization of the magnet 4 to effect closure of the switch, tail piece 17 is entirely free to move away from the pin 19. Upon opening of the switch, tail piece 17 engages pin 19 and the buffer device then acts to frictionally dissipate the kinetic energy present in the moving switch parts and to bring the moving switch parts to rest in normal position without rebound.

Upon closure of the switch under the action of the magnet 4 the movable contacts 2 engage their cooperating stationary contacts 1 prior to full movement of armature 16 into its attracted position and upon continued movement of armature 16 towards its attracted position rocker arm 7 moves with respect to lever 9 against the action

of spring 11. Also upon closure of the switch equalizer lever 5 assumes a position wherein the movable contacts 2 are aligned with the stationary contacts 1 and during opening of the switch said equalizer lever is maintained in such position to insure simultaneous disengagement of said contacts.

The above described switch may be used in control systems of various types and is particularly adapted for use in welding timers of the type disclosed in my copending application Serial No. 100,279, filed September 11, 1936. In order to set forth the function and operation of the aforescribed switch a simplified showing of a timing controller of the character disclosed in my aforementioned application is included in Fig. 1. The switch is connected to supply current from a single phase alternating current supply circuit indicated by lines L¹—L² to the welding circuit (not shown) through the medium of a transformer T. The timing control means shown includes a condenser 23, a pilot switch 24, a rectifier 25 and a gaseous electron tube 26 having a heated cathode 26^a, a grid 26^b and an anode 26^c. Pilot switch 24 is provided with normally closed contacts 24^a and normally open contacts 24^b and the former contacts serve to normally connect condenser 23 and rectifier 25 in series across a single phase alternating current circuit indicated by lines L³—L⁴ to effect charging of said condenser. However, upon opening of contacts 24^a and closure of contacts 24^b of the pilot switch the operating winding 15 of the switch is connected in series with condenser 23 through the medium of tube 26 and said condenser then discharges through said winding to effect response of the switch by a single unidirectional current impulse. Grid 26^b is controlled by means not shown in the drawings, but disclosed in my aforementioned copending application, to provide for discharge of condenser 23 through the operating winding 15 of the switch only at a definite point in the A. C. cycle of the supply circuit L¹—L².

In accordance with the present invention condenser 23 is adjusted to provide a unidirectional current impulse which is of sufficient value to effect rapid movement of contacts 2 into engagement with their associated stationary contacts 1 but insufficient to effect acceleration of the moving switch parts after the contacts are brought into engagement. Upon arrest of the movable contacts in circuit closing position the moving switch parts continue to move inwardly against the action of spring 11, and said spring is so adjusted that inward movement of said parts is arrested prior to sealing of armature member 16 with the pole faces of magnet frame 14. Thus upon closure of the switch substantially the entire energy present in the moving switch parts is stored in spring 11, and upon cessation of inward movement of said parts the same are accelerated in circuit opening direction under the action of said spring. It is thus apparent that the speed at which the contacts 2 are moved out of engagement with the stationary contacts 1 is substantially the same as the speed at which said movable contacts are moved into engagement with said stationary contacts. In practice it has been found that when the switch is energized by a current impulse of a given value the interval during which the contacts remain in closed position is substantially proportional to the degree of continued movement of the moving switch parts which occurs after the contacts are moved into closed position. Thus by varying the degree of compression of spring 75

11 the degree of inward movement of the moving switch parts after the contacts are brought into engagement may be varied to vary the periods of power application in the welding circuit. In practice it has been found that a switch constructed and operated as above described is adapted to provide exceedingly small and accurately controlled periods of power application corresponding to as low as 1/2 cycle of the current in the supply mains L¹—L².

Referring now to Figs. 2 to 6, inclusive, the same illustrate a mechanical embodiment of the switch schematically illustrated in Fig. 1. As shown in Fig. 2, the switch is mounted upon a vertical insulating panel 28, and each pole thereof has a blowout device 29 associated therewith of the construction disclosed in the copending application of T. B. Jochem et al., Serial No. 217,194, filed July 2, 1938. Each of the stationary contacts 1 is fixed to the front end of an arc horn 30 associated with its respective blowout device (Fig. 4) and each of said arc horns is mounted upon the front face of panel 28 and is connected to a terminal element 31 through the medium of a blowout coil 32.

The movable contacts 2 are fixed to brackets 33 which are mounted upon insulated arms 34 of equalizer lever 5 and each of said contacts has a flexible lead 35 associated therewith which is connected to a terminal element 36 mounted upon the front face of insulating panel 28. As hereinbefore stated, equalizer lever 5 is pivotally mounted intermediate its ends upon a rocker arm 7. As shown in Fig. 5, said equalizer lever is provided with a forwardly extending projection 37 having an upwardly extending spindle 38 formed on the upper side thereof which is rotatably supported within an opening in a bearing projection 39 formed on the upper end of rocker arm 7. The upper face of projection 37 on equalizer lever 5 is held in frictional engagement with the lower face of bearing projection 39 by a screw 40 extending through an opening in spindle 38. As shown in Fig. 5 the upper end of screw 40 has a spring washer 41 associated therewith which is held under compression against the upper face of bearing projection 39 by a nut 42 on the upper end of said screw.

As hereinbefore stated, and as shown in Fig. 5, rocker arm 7 extends downwardly and rearwardly with respect to equalizer lever 5 and is pivotally mounted intermediate its ends upon a pin 8 carried by a lever 9 fixed to operating shaft 3. Also as hereinbefore set forth, the lower end 50 of rocker arm 7 is normally held in engagement with a stop projection 10 on lever 8 by a spring 11 which is adjustable by a screw device 12 carried by a forwardly projecting lug 13 on lever 9.

As shown in Fig. 5, the upper end of spring 11 is held within a recess in the underside of projection 37 on equalizer lever 5 and the screw device 12 is associated with the lower end of said spring. Screw device 12 includes an internally threaded bushing 43 which contains a screw 44 having an enlarged head 45 on the upper end thereof for engaging the lower end of spring 11. Bushing 43 is rotatably mounted within an opening in projection 13 on lever 9 and the lower end of said bushing has an adjusting knob 46 fixed thereto, while the upper end thereof is provided with an enlarged circular head 47 which engages the upper face of said projection. Head 47 of bushing 43 has teeth formed on the periphery thereof and said bushing is releasably held against rotation by a spring pressed ball 48 which engages said

teeth and is supported within a drilled opening in the hub portion of lever 9. Screw 44 is held against rotation by a pin 49 which is fixed to the head 45 of said screw and extends forwardly into a vertical slot 50 in a U-shaped gauge member 51 mounted upon projection 13 of lever 9.

Upon rotation of sleeve 43 by knob 46 the screw 44 is adjusted vertically to vary the degree of compression of spring 11. As hereinbefore set forth, the period of power application in the welding circuit is determined by the degree of compression of spring 11. As is apparent, the position of pin 49 within the slot 50 indicates the degree of compression of spring 11 and in practice the front face of gauge member 51 is provided with markings 52 for indicating the periods of power application which result from various settings of said spring.

As shown in Fig. 2, the right end of shaft 3 is journaled upon a pin 53 carried by a bracket 54 mounted upon the front face of insulating panel 28 and the left end of said shaft is journaled upon a pin 55 carried by a bracket 56 associated with the magnet frame 14 of operating magnet 4. Bracket 56, as shown in Fig. 3, is secured to the front face of insulating panel 28 by bolts 57 and the same is provided with two forwardly extending arms 58 and 59 which carry the pin 55.

Armature member 16 of magnet 4 is rotatably mounted upon pin 55 and is operatively connected to shaft 3 through the medium of a downwardly extending lever 60 which is fixed to said shaft. As shown in Fig. 2, the lower end of lever 60 is provided with a horizontal extension 61 having a vertical face 62 which is engaged by a bushing 63 mounted within an opening in the tail piece 17 of armature member 16. Bushing 63 is clamped against the vertical face 62 of lever 60 by a screw 64 which extends through the opening in said bushing and is threaded into the extension 61 on said lever. The opposing faces of bushing 63 and extension 61 on lever 60 are formed to provide interlocking teeth 65 and as is apparent said teeth provide a rigid coupling between armature member 16 and said lever. The interlocking teeth 65 on bushing 63 and extension 61 extend in the direction shown in Fig. 3, and as is apparent upon loosening screw 64 lever 60 may be adjusted with respect to bushing 63 to vary the angular position of shaft 3 and its associated contacts 2 with respect to armature member 16. Such adjustment provides for variation of both of the air gaps between movable contacts 2 and their associated stationary contacts 1 and it should be noted that the equalizing mechanism associated with movable contacts 2 renders it practical to employ a single means for effecting adjustment of both of the air gaps.

As hereinbefore stated, the switch is provided with a buffer device 18 which is associated with armature member 16 and acts to effect arrest of the moving switch parts in open position without rebound. As shown in Fig. 3, the housing 21 of said buffer device is mounted upon the rear face of insulating panel 28 and the headed pin 19 which cooperates with the tail piece 17 of armature member 16 extends forwardly through an opening in said panel.

What I claim as new and desire to secure by Letters Patent is:

1. In a timing controller for an electric circuit, in combination, a normally open switch for controlling said circuit, an operating member therefor, a spring operating connection between said member and said switch acting upon movement

- of said operating member in one direction out of a given normal position to effect closure of said switch, said spring operating connection permitting overtravel of said operating member upon closure of said switch, a power operated device responsive to move said operating member out of normal position, and means for controlling said device to provide for movement of said operating member out of normal position under the action of a predetermined power impulse to effect closure of said switch and to also effect over-travel of said operating member after closure of said switch solely by inertia against the action of said spring operating connection to thereby provide for momentary closure of said switch.
2. In a timing controller for an electric circuit, in combination, a normally open switch for controlling said circuit, an operating member therefor, a spring operating connection between said member and said switch acting upon movement of said operating member in one direction out of a given normal position to effect closure of said switch, said spring operating connection permitting overtravel of said operating member upon closure of said switch, electroresponsive means for moving said operating member out of normal position, means for energizing said electroresponsive means by a predetermined power impulse to effect closure of said switch and to also effect over-travel of said operating member after closure of said switch solely by inertia against the action of said spring operating connection to thereby maintain said switch in closed position for an interval which is substantially proportional to the degree of over-travel of said operating member, and means for adjusting said spring operating connection to vary the degree of over-travel of said operating member under the action of said predetermined power impulse.
3. In a timing controller for an electric circuit, in combination, a switch for controlling said circuit, said switch including a plurality of movable contacts biased to open position and providing a plurality of gaps in said circuit, an operating member for said switch, a single spring operating connection between said operating member and said movable contacts acting upon movement of said operating member in one direction out of a given normal position to move said contacts into closed position, said spring operating connection permitting over-travel of said operating member upon closure of said contacts, an electroresponsive device for moving said operating member out of normal position, means for operating said device by a predetermined current impulse to effect movement of said contacts into closed position and to also effect over-travel of said operating member after closure of said contacts solely by inertia against the action of said spring operating connection to thereby maintain said contacts in closed position for an interval which is substantially proportional to the degree of over-travel of said operating member, and means for adjusting said spring operating connection to vary the degree of over-travel of said operating member for variation of the interval during which said contacts are maintained in closed position.
4. In a timing controller for an electric circuit, in combination, a control switch including a plurality of movable contacts biased to open position and providing a plurality of gaps in said circuit, an operating magnet therefor including a stationary magnet frame and a cooperating movable armature member, a single spring operat-

ing connection between said armature member and said movable contacts for effecting closure of the latter upon attraction of said armature member out of a given normal position, said spring operating connection permitting overtravel of said armature member upon closure of said contacts, and means for energizing said operating magnet by a current impulse which is of a given value to effect closure of said contacts and to also effect overtravel of said operating member upon closure of said contacts solely by inertia against the action of said spring to temporarily maintain said switch in closed position for a period which is substantially proportional to the degree of overtravel of said armature member.

5. In a timing controller for an electric circuit, in combination, a control switch for said circuit including a plurality of movable contacts biased to open position and providing a plurality of gaps in said circuit, an operating magnet therefor including a stationary magnet frame and a cooperating movable armature member, a single spring operating connection between said armature member and said movable contacts for effecting closure of the latter upon attraction of said armature member out of a given normal position, said spring operating connection permitting overtravel of said armature member upon closure of said contacts, means for energizing said operating magnet by a current impulse which is of a given value to effect closure of said contacts and to also effect overtravel of said armature member upon closure of said contacts solely by inertia against the action of said spring to maintain said contacts in closed position for a period which is substantially proportional to the degree of overtravel of said armature member, means for adjusting said spring to vary the degree of inertial overtravel of said armature member, and means associated with said adjusting means for indicating periods of closure of said switch corresponding to different settings of said spring.

6. An electromagnetically operated control switch comprising a pair of stationary contacts, movable contacts cooperating with said stationary contacts and biased out of engagement therewith, an equalizer lever carrying said movable contacts, said equalizer lever being bodily movable to effect simultaneous operation of said movable contacts and being pivotally supported to permit self-alignment of said movable contacts with respect to said stationary contacts, an operating magnet for said movable contacts including a stationary operating winding and a movable armature member to be attracted out of a given normal position by said winding, and a single spring operating connection between said armature member and said equalizer lever for moving said movable contacts into circuit closing position upon attraction of said armature member out of normal position, said spring operating connection permitting overtravel of said armature member upon closure of said movable contacts.

7. An electromagnetically operated control switch comprising a pair of stationary contacts, movable contacts cooperating therewith, an equalizer lever carrying said movable contacts, said lever being bodily movable to simultaneously operate said movable contacts and being pivotally supported intermediate said movable contacts to permit self-alignment of the latter with respect to said stationary contacts, a rotatable

operating member, an arm pivotally mounted upon said operating member and carrying said equalizer lever, a spring normally holding said arm in a given angular position with respect to said operating member, an operating magnet including a stationary operating winding and a movable armature member fixed to said operating member, said armature member being biased toward a given normal position to maintain said movable contacts in open position and being movable out of normal position by said winding to move said movable contacts into closed position through the medium of said spring and said armature member being capable of overtravel against the action of said spring upon arrest of said movable contacts in closed position.

8. An electromagnetically operated control switch comprising a pair of stationary contacts, movable contacts cooperating therewith, an equalizer lever carrying said movable contacts, said lever being bodily movable to operate said contacts simultaneously and being pivotally supported intermediate said movable contacts to permit self-alignment of the latter with respect to said stationary contacts, a rotatable operating member, an arm pivotally mounted upon said operating member and carrying said equalizer lever, a spring normally holding said arm in a given angular position with respect to said operating member, an operating magnet including a stationary operating winding and a movable armature member fixed to said operating member, said armature member being biased toward a given normal position to maintain said movable contacts in open position and being movable out of normal position by said winding to move said movable contacts into closed position through the medium of said spring, said armature member being also capable of overtravel against the action of said spring upon arrest of said movable contacts in closed position, and means for adjusting said spring to vary the opposing action thereof upon overtravel of said armature member.

9. An electromagnetically operated control switch comprising a pair of stationary contacts, movable contacts cooperating therewith, an equalizer lever carrying said movable contacts, said lever being bodily movable to operate said contacts simultaneously and being pivotally supported intermediate said movable contacts to permit self-alignment of the latter with respect to said stationary contacts, a rotatable operating member, an arm pivotally mounted upon said operating member and carrying said equalizer lever, a spring normally holding said arm in a given angular position with respect to said operating member, an operating magnet including a stationary operating winding and a movable armature member fixed to said operating member, said armature member being biased toward a given normal position to maintain said movable contacts in open position and being movable out of normal position by said winding to move said movable contacts into closed position through the medium of said spring, said armature member being also capable of overtravel against the action of said spring upon arrest of said movable contacts in closed position, means for adjusting said spring to vary the opposing action thereof upon overtravel of said armature member, and means for adjusting said operating member with respect to said armature member for variation of the air gaps between said stationary and movable contacts.

10. An electromagnetically operated control switch comprising a pair of stationary contacts, a movable contact cooperating with said stationary contacts and biased out of engagement therewith, an equalizer lever carrying said movable contacts, said equalizer lever being bodily movable to effect simultaneous operation of said movable contacts and being pivotally supported to permit self-alignment of said movable contacts with respect to said stationary contacts, an operating magnet for said movable contacts including a stationary operating winding and a movable armature member to be attracted out of a

5 given normal position by said winding, a single spring operating connection between said armature member and said equalizer lever for moving said movable contacts into circuit closing position upon attraction of said armature member out of normal position, said spring operating connection permitting overtravel of said armature member upon closure of said movable contacts, and means for adjusting said equalizer lever with respect to said armature member to provide for variation of the normal air gaps between said stationary and movable contacts.

CARROLL STANSBURY.
